UNITED STATES PATENT OFFICE.

JOSEPH M. KROWKA, OF GEORGE WEST, TEXAS.

AEROPLANE-TAIL.

1,365,704.

Specification of Letters Patent. Patented Jan. 18, 1921.

Application filed May 27, 1919. Serial No. 300,168.

To all whom it may concern:

Be it known that I, JOSEPH M. KROWKA, a citizen of the United States, residing at George West, in the county of Live Oak and State of Texas, have invented certain new and useful Improvements in Aeroplane-Tails; and I do hereby declare the following to be a full, clear, and exact description of the invention, such as will enable others skilled in the art to which it appertains to make and use the same.

This invention has reference to aeroplanes, and it refers in particular to a novel construction of the aeroplane tail, and of the aeroplane body, and to the way of connecting these parts with each other and to the seat of the aviator, and it is one of the chief objects of my invention to provide a tail construction which may be utilized as a self-governing means to direct and to control the flight of any suitable heavy body, a projectile or the like which is projected through the air, and which, when used in connection with an aeroplane under the control of an aviator is easy of operation, and the different positions of which will not influence the equilibrium of the aeroplane and of the seat of the aviator. It is a further object of my invention to devise a novel combination of a horizontal with a vertical tail surface, and also to devise means whereby the body of the aeroplane may be caused to move independently of the tail surfaces, and in a certain manner independently of the weight suspended therefrom or carried thereby, and without interfering with the perfectly perpendicular position of the latter.

Other objects and advantages of my invention not specially enumerated herewith will be apparent from the following specification and from the drawings showing an aeroplane as an instance to which my invention may be applied.

In the drawings:—Figure 1 is a longitudinal section of an aeroplane constructed in accordance with my invention. Fig. 2 is a plan view of the same. Fig. 3 is a section of Fig. 1 on the line 3—3; Fig. 4 is a section of Fig. 1 on the line 4—4; Fig. 5 is a section taken substantially on line 5—5 of Fig. 2; Fig. 6 is a detail underneath view of the controlling disk for the vertical tail; Fig. 7 is a detail of the means for locking the controlling disk in rotary adjustment; Figs. 8 and 9 are diagrams to be referred to.

1 is a horizontal and 2 is a substantially vertical tail. 3 is a bar preferably arranged between the broader part 1 and the reduced part 1' of the horizontal tail and secured to the same. 7 is a vertical pivot mounted on said bar 3 and constituting the rotating center for the vertical tail 2. 5 is a vertical frame secured to the bar 3, and preferably containing the operating means for the horizontal tail. The bar 3 is provided with lateral projections extending beyond the tail and to which the vertical frame 5 is secured. Between the frame 5, and preferably between the broader part 1 and the reduced part 1' of the horizontal tail collars or the like 29 are arranged which are provided with hinges 4, and to which the body part 8 of the aeroplane is hingedly connected. 9 is a rotatable shaft mounted in suitable bearings in the front part of the frame or body part 8 and connected with the downwardly extending supporting frame 10 to which a balancing weight is attached which by reason of the transverse shaft 9 being loosely mounted in its bearings will always assume a perfectly perpendicular position. In the construction shown as an instance in the drawings the aviator's seat 11 is secured to the support 10 and serves as a weight. The shaft 9 projects on both sides of the frame 8, and upon its projecting ends are secured levers or bars 13 from which rods or cords 14, 15 and 14', and 15' respectively extend to the upright frame 5 at the rear part of the aeroplane. 33 are guides which may be provided on both sides of the body frame 8 and serve for guiding the rods or cords 14, 15, 14', and 15'. 12 is a handle or the like which in the present instance is preferably of semi-circular or similar shape and arranged at one or both sides of the inside of the body part 8 within easy reach of the aviator on the seat 11. Cross ties 20 and 40 respectively connect the opposite sides of the frame 8. The cross ties 20 at the forward end of the aeroplane serve for the mounting of a circular adjusting disk 16 provided with a handle 17 within easy reach of the operator and preferably situated opposite the semi-circular handle 12. Rods or cords 18 and 19 or the like connect said disk 16 to a cross bar 6 secured by means of braces 30 or otherwise to the vertical tail 2, and at substantially right angles thereto. By means of the rotation of the wheel or disk 16 the vertical tail 2 may be rotated

on its pivot 7, and adjusted to any desired horizontal angle. At the same time the vertical tail in all its adjustments will follow the vertical inclination of the horizontal tail 1 upon which it is mounted. The operation of the horizontal tail is effected by means of the seat support and the parts associated therewith, which may be shifted by means of handles 12 secured to the body frame 8, and preferably arranged within easy reach of the aviator. An arcuate rack bar 24 is arranged in the lower part of the body frame 8 and below the seat 11 of the aviator, and a locking pin or the like 25 is arranged on said seat 11, and preferably within easy reach of the foot of the aviator, and may be depressed to engage with said rack bar 24 so as to lock the seat in a certain angular position with regard to the body frame 8. In the inoperative position the pin 25 is withdrawn from engagement with the rack bar 24 by an encircling spring. 28 is a suitable propelling device of any preferred construction at the front end of the aeroplane, and 32 is a plane which may be arranged, if desired, at the front part of the body frame 8. Bracing wires or cords or the like 26 extend between the horizontal tail 1 and the bar 3, and similar bracing members 26 extend between the tail 1 and the upright supporting frame 5, and similar bracing members 30 are likewise arranged between the sides of the frame 5, and between the cross bar 6 and braces 31 of the vertical tail 2 and the frame 5, and other preferred means not shown in the drawings may be employed alone or in connection with those shown in the drawing for the purpose of bracing the parts, and preventing injury by the pressure of the wind or from other causes.

By varying the inclination of the body frame 8 with regard to the other parts of the aeroplane an ascending or downward movement is imparted to the device. This inclination is produced by the aviator grasping the handle or the semi-circular bar 12 and rotating said part 8 on its pivots 4 thereby either raising or lowering his weight relatively to the frame 8. In order to cause the aeroplane to ascend the seat which constitutes the balancing weight of the device is moved to the front by depressing the front end of the aeroplane, while, when it is desired to descend the seat or weight is moved to the rear by depressing the rear end of the aeroplane by means of the handle 12. This causes the horizontal tail 1 to rock downwardly on the hinges 4. By inserting the locking pin 25 between the teeth of the rack 24 the aeroplane is locked in the adjusted positions for ascent or descent, respectively, and by operating the handle 17 and thereby turning the wheel 16 the vertical tail 2 is rotated on its pivoting pin 7 without affecting

the inclination of the horizontal tail 1, 1'. Holes 34 may be arranged near the periphery of the wheel 16 for the insertion of a locking pin 35 for the purpose of retaining the wheel 16 in the adjusted position, the locking pin entering a corresponding hole in one of the cross ties 20. The wheel 16 is preferably arranged right in the median line of the aeroplane and at the inside of the top cross frame immediately above the head of the aviator.

Fig. 8 illustrates diagrammatically the position of the parts when the aeroplane unexpectedly takes a downward curve, and Fig. 9 illustrates diagrammatically the position of the parts when the aeroplane unexpectedly takes an upward curve. In every case the weight or the seat retains its absolutely perpendicular position, and the body part 8 being pivoted to the seat or weight follows its upward and downward movement without affecting the relative angular positions of the combination of tails, so that the tails may be said to be self-adjusting. This is a point of great importance connected with my invention, inasmuch as by this means the safety of the operator or of the weight carried in the seat or support 11 is insured, and in view thereof my invention may be used for automatically controlling the movement of projectiles, such as aerial torpedoes for instance which may be provided with the instrumentalities constituting my invention, the projectile or explosive taking the place of the weight or seat 11 of the aviator, and by this means an absolutely pilotless aeroplane is produced which is automatically controlled by the self-governing combination of tails in accordance with my invention.

Marks or informative matter relating to the directions of the compass or similar information may be provided on the wheel or disk 16, and other modification and changes may be resorted to in connection with my invention in order to more successfully adapt the device to varying local conditions, and without deviating from the spirit of my invention as set forth in the claims hereunto appended.

Having described my invention what I claim is:—

1. In an aeroplane, the combination with a frame, and a horizontal adjustable tail, of an inverted U-shaped frame overlying the tail, a vertically disposed tail including trunnions journaled in the U-shaped frame and the horizontally adjustable tail respectively, and a swinging seat suspended in the frame having operative connection with the side bars of the U-shaped frame where upon movement of the seat with respect to the center of gravity the inclination of the horizontally adjustable tail will be varied.

2. In an aeroplane, the combination with

5 a frame and a horizontal adjustable tail, of a U-shaped frame extending vertically from the tail, a vertically disposed tail having one end journaled upon the horizontally adjustable tail and its opposite ends journaled in the U-shaped frame, a rock shaft journaled in the aeroplane frame, bars fixed to the shaft, operative connections between the bars and the vertical legs of the U-shaped 10 frame, and means for moving the shaft axially to change the position of the horizontally adjustable tail.

15 3. In an aeroplane, a frame, a tail pivoted at one end of the frame to swing on a horizontal axis, a seat suspended from the top of the frame to swing on a horizontal axis, a longitudinally curved toothed bar

20 mounted upon the bottom of the frame and extending longitudinally thereof, a locking element carried by the seat and adapted for engagement with the toothed bar to hold the seat in various angular positions with respect to the center of gravity, and operative connections between the seat and tail whereby to change the relative angle of the 25 latter upon movement of the seat upon its axis.

In testimony whereof I affix my signature in presence of two witnesses.

JOSEPH M. KROWKA.
